UNITED STATES PATENT OFFICE.

GEORGE ALBEN E. LUNDELL, OF NEW YORK, N. Y.

TELEPHONE-EXCHANGE SYSTEM.

Application filed April 11, 1921, Serial No. 460,271. Renewed January 8, 1927.

This invention relates to telephone exchange systems, and more particularly to trunk circuits to operators in telephone exchange systems employing automatic selectors.

It is the object of the present invention to provide an improved operator's trunk circuit in which several functions may be accomplished, with a minimum of expense and equipment.

Another object relates to a manually operable means for predetermining the degree of movement of a rotary switch adapted during such movement to send impulses of current.

Another object relates to the selection of coin box operating currents of varying character and selective signalling currents of varying character, by means of a single selecting instrumentality.

Other objects will appear as the description of the invention progresses.

The present embodiment is one of a variety of forms in which the invention may be practiced, and it is understood that the scope of the invention is not to be determined by such disclosure, reference being had to the appended claims for that purpose.

30 Referring to the drawings,

Figure 1 shows a pair of calling lines, and diagrammatically a link circuit for extending a telephonic connection;

Figure 2 shows the outgoing end of a 35 trunk to an operator; and should be placed to the right of Figure 1;

Figure 3 shows the incoming end thereof, and a cord circuit with a rotary switch, and should be placed below Figure 2.

40 Referring to the drawings, upon making a call from station 601 for station 274, a coin 602 is placed in the coin box 603, and the receiver is removed from its hook. Station 601 is joined to the central office by 45 means of a pair of conductors 604, 605, and is provided at the central office end thereof with a usual line and cutoff relay. The connection may be extended in any well known manner to operator's trunk circuit 248, 249, 50 266. The link circuit interconnecting said line and said trunk circuit may consist of finder 29 and selector 30 such as shown and described in my co-pending application Serial Number 457,757 filed April 1, 1921, or 55 any other suitable mechanism. The regis-

ter sender shown within the dash dot line of Figure 1, after causing the establishment of such connection restores to normal and also causes the sequence switch of power magnet 49 to move to position 14.

60 The sequence switches shown in various parts of the drawings comprise sets of contacts such as 620 adapted to close contacts in the various positions of the sequence switch. The numerals which appear adjacent thereto indicate the positions of the sequence switch at which such contacts are closed; with the exception that the centering spring, shown immediately above the power magnet is open only at the positions indicated by the numerals adjacent to it and therefore the sequence switch can stop only in these positions. Motor mechanism is provided for rotating the sequence switch through its successive positions. This mechanism is employed during the energization of the power magnet for driving the sequence switch.

When a call is originated by a subscriber 80 the sequence switch 49 is moved out of position 1 by the operation of suitable line and control relays (not shown) in a manner well known in the art. The wipers 57, 58 and 59 are advanced over sets of terminals with which they co-operate and are stopped in 85 contact with the terminals of a calling line. A busy test condition is placed upon the test conductor of a line by way of sequence switch contact 65 resistance coil 69 to a source of test potential 68. Connection is 90 also established for the purpose of registration to a register sender over conductors 70, 71 by way of sequence switch contacts 73, 76 to control relay 72 whereby the register

95 sender may be adjusted in well known manner under control of the calling device at the calling subscriber's station in accordance with the wanted subscriber's line number. The sequence switch 49 is advanced to position 10. The wipers 116, 117, 118 of the selector switch 30 are advanced over sets of terminals with which they co-operate and into contact with a set of terminals in a desired group in well known manner and in 100 accordance with the adjustment of the register sender. Upon completion of registration the selection relay 203 is operated in a well known manner and closes a circuit from ground to battery, winding of power magnet 49, sequence switch contact 243, conductor 110

242, front contact and armature of relay 203 to ground. The sequence switch 49 is advanced out of position 10 and through position 13 into position 14. A circuit is now closed from ground, sequence switch contact 126, left-hand winding of relay 103 to grounded battery 104 thereby operating relay 103. A circuit is now closed from grounded battery, winding of repeating coil 246, Fig. 10, 2, winding of relay 607, right-hand back contact and armature of 606, conductor 249, wiper 117, Fig. 1, sequence switch contact 73, wiper 58, conductor 605, subscriber's station 601, conductor 604, wiper 59, sequence switch 15, contact 76, conductor 163, wiper 118, conductor 248, left-hand back contact and armature of relay 606, Fig. 2, winding of repeating coil 246 to ground, thereby operating relay 607. A circuit is now closed from grounded battery 262, Fig. 3, winding of relay 252, armature and back contact of relay 253, conductor 254, winding of repeating coil 246, Fig. 2, front contact and armature of relay 607, right-hand back contact and armature of relay 264, winding of relay 219 to ground thereby operating relay 219. Relay 103 closes a locking circuit for itself comprising grounded battery 104, right-hand winding and front contact and armature of relay 103, sequence switch contact 129, wiper 116, conductor 266, and armature and front contact relay 219, winding of transformer 267 to ground. A circuit is also closed from ground, left-hand armature and front contact of relay 103, sequence switch contact 47, winding of power magnet 49, to grounded battery for moving the sequence switch 49 out of position 14 and into position 15.

40 Reference characters below 400 refer to like parts in the application cited above.

The circuit above described for operating relay 219 included also the winding of relay 252, and this relay operated thereby closes the local circuit including the lamp 265 and causes the illumination of the lamp.

While passing through position 14, sequence switch contacts 73, 76 momentarily connect relays 172, and 607 in parallel, but this condition is only temporary and produces no effect upon the operation of the system.

The lighting of lamp 265 attracts the attention of an operator. She inserts plug 55, 268 into jack 239 closing a circuit for the winding of relay 253. The operation of relay 253 cuts off relay 252, the consequent release of which extinguishes lamp 265. The operator actuates listening key 271 to place herself in telephonic communication with station 601.

A circuit is also closed from grounded battery 269, windings of repeating coil 273 and signal 270, contact of key 609, plug 268, jack 239, conductor 254, winding of repeating coil

246, contact of relay 607, windings of relays 259, 610 and repeating coil 246, left hand back contact and armature of relay 614, conductor 261, jack 239, plug 268; key 609, winding of repeating coil 273 to ground, operating relay 259 and signal 270. Relays 259 and 610 are polarized relays, and the current now flowing through their windings operates relay 259 but not 610. Relay 259 closes a circuit from grounded battery, winding of relay 264, armature and front contact of relay 259, right hand winding of relay 263 to ground, operating relay 264 and 263. Relay 264 breaks the circuit of slow release relay 219 which releases, but relay 264 maintains the connection of conductor 266 to ground.

The operator establishes a desired connection to station 274 in any suitable manner, employing well known connecting means such as cords, plugs and jacks.

The operator ascertains the class of service of the calling line by listening for the class of service signal tone on the test conductor of his line. This she does by actuating key 609 (leaving key 271 also operated). A circuit is closed from grounded battery, windings of repeating coil 273 and signal 270, uppermost contact of key 609, sequence switch contact 611, left hand back contact and armature of relay 612, contact 613 of key 609, plug 268, jack 239, conductor 261, left hand armature and back contact of relay 614, windings of repeating coil 246 and relays 610, 259, contact of relay 607, winding of repeating coil 246, conductor 254, jack 239, plug 268, contact 615 of key 609, winding of repeating coil 273 to ground. It will be noted that current through windings of relays 610 and 259 is reversed, consequently relay 259 releases and relay 610 operates. A circuit is closed from ground, armature and front contact of relay 610, winding of slow release relay 614 to grounded battery, operating relay 614. The operation of this relay opens a short circuit around the winding of relay 616, but relay 616 is marginal and will not operate on low voltage battery 269. Relay 614 closes, at its extreme right hand front contact, a circuit for maintaining operated relay 264, independent of relay 259. A circuit is closed from ground, lowermost contact of key 609, sequence switch contact 617, winding of relay 618 to grounded battery, operating relay 618. A circuit is closed from ground, armature 619 and front contact of relay 618, sequence switch contact 620, winding of power magnet 621 to grounded battery, for moving the sequence switch of Figure 3 to position 2.

The operator now actuates master key 623, closing a circuit from ground, armature 619 and front contact of relay 618, key 623, sequence switch contact 624, winding of power magnet 621 to grounded battery, for moving

the sequence switch out of position 2, and under control of its centering spring 622 into position 4. In position 3, the circuit of relay 610 is momentarily broken once at 5 sequence switch contact 611. This releases relay 610 momentarily, and closes once a circuit from ground, armature and back contact of relay 610, armature 625 and front contact of slow release relay 614, winding 10 of magnet 626 to grounded battery.

Magnet 626 forms part of a step by step selector switch 627, comprising also a ratchet wheel 628, wiper arms 629, 630, 631, 632, each of which is provided with a row of contacts, with which they contact in sequential order, and after being stepped away from the last contacts of their rows, they are brought into engagement again with the first or normal contacts.

20 Said wiper arms are moved from their first to their second contacts by the single operation of magnet 626 described. A circuit is closed from ground, upper contact of key 623, sequence switch contact 617 for 25 maintaining relay 618 energized independent of key 609. Although the original energizing circuit of this relay is opened by the lower sequence contact 617, this relay is locked through its right hand front contact 30 independently thereof. A circuit is closed from ground, armature 619 and front contact of relay 618, key 623, sequence switch contact 633 (this sequence switch is in its 35 fourth position), winding of relay 612 to grounded battery, for operating relay 612. A circuit is now closed from high voltage 40 grounded battery 634, coil 635, left hand front contact and armature of relay 612, contact 613 of key 609, plug 268, jack 239, conductor 261, windings of marginal relay 616, repeating coil 246 and relays 610, 259, 45 winding of repeating coil 246, conductor 254, jack 239, plug 268, contact 615 of key 609, winding of repeating coil 273 to ground, operating relay 616 and retaining relay 610 operated.

A circuit is closed from ground, armature and front contact of relay 616, arm 632 on 50 its second contact, winding of relay 636 to grounded battery, for operating relay 636. Thus the secondary winding of the induction coil 267 is connected to conductors 254, 261 and the operator may overhear the class 55 of service tone. The inductive connection includes condensers 637, 638 and 639.

The operator recognizes the distinctive tone; in the present case she recognizes it as that of a coin box line. She releases key 623 and this in turn releases relays 612, 616, 60 636. Assuming that the connection has been completed, and that it is not a free call, the operator advises the calling party how much additional money is to be deposited by him, if any. As the coins drop into the box, they 65 produce distinctive audible signals, in a well

known manner. She then operates key 640 and thus closes a circuit for the power magnet 621, in a manner similar to that described above, for moving the sequence switch into position 8. During this movement, sequence switch contact 611 twice breaks the circuit of relay 610 momentarily, again actuating magnet 626 twice and moving wiper arms 629, 630, 631, 632 two steps, to their fourth contacts. In position 8, relay 70 75 80 85 90 95 100 105 110 115 120 125 130 magnet 626 to grounded battery, operating relay 606. A circuit is closed from grounded high voltage source 641, winding of relay 642, arm 629, left hand front contact and armature of relay 606, conductor 248, wiper 118, conductor 163, sequence switch contact 76, wiper 59, conductor 604, winding and contact of coin box 603 to ground at station 601. The voltage and polarity of source 641 are such as to operate the magnet of the coin box 603 in a direction to deposit the money. Relay 642 operates and inductively connects an interrupter 644 to the repeating coil 246, producing a tone in the operator's receiver 272 as a check on the operation of the coin box. Release of key 640 deenergizes relays 612, 616, 606 and 642.

The operator may now restore key 609 to normal. Relays 618, 610, 614 are released and relay 259 again operates. The release of relay 618 closes a circuit from ground, armature 619 and back contact of this relay, sequence switch contact 620, power magnet 621 to grounded battery for restoring the sequence switch to its normal position. Release of slow release relay 614 closes a circuit from ground, armature and back contact of relay 610, armature 625 and back contact of relay 614, arm 631, winding of relay 664 to grounded battery. Relay 664 operates and locks to arm 631 independently of said relays. A circuit is closed from ground, left hand armature and front contact of relay 664, arm 631 on any of its off normal contacts, right hand contact of relay 664, back contact and winding of magnet 626 to grounded battery. Thus magnet 626 is intermittently operated until switch 627 is fully restored. Relay 664 then releases, its circuit being controlled by arm 631.

Upon completion of conversation, signal 270 releases when relay 607 releases, as it is adjusted not to remain operated in series with the high resistance winding of relay 263, and the operator pulls down plug 268. This deenergizes and releases relays 253, 259, 264, 263, 103. Relay 103 causes the restoration to normal of the link circuit of Figure 1 in the manner described in the above mentioned application.

Had she so desired, the operator might have returned the coin 602 to the calling party. She would then have used key 645. The sequence switch of Figure 3 would have been advanced only to position 6 and switch 627 to its third contacts. Thus source 646 would have been made active instead of source 641. The polarity of source 646 is such as to cause the magnet of coin box 603 to eject the money. The operation of relay 647 connects a different interrupter 648 to talking set 272.

Ringing back.

Assuming a call from station 650 for station 274, the operation is similar to that already described up to the point where the class of service indication is obtained. Station 650 being a party line station, there is connected to the test conductor 653 of its line a differently characterized source 654 of tone current. This the operator recognizes as being that of a four party line, it being assumed that there are four stations connected to line conductors 651, 652.

The sequence switch of Figure 1 is at this time in position 15, that of Figure 3 in position 4, and switch 627 on its second contacts. If the operator anticipates a delay in completing the connection to wanted station 274, she may ask the calling party to replace his receiver on its hook until she signals him. When he does so relay 607 releases, opening a short circuit around the left hand windings of relays 263 and 610. The windings of relay 263 are connected so as to be at this time mutually aiding. Let it be assumed that meanwhile the operator has other use for master keys 623, 645, 640, 655, etc., say in connection with another cord circuit. She releases key 609. This releases relays 618, 610, 614 and restores switch 627 to normal as before. The sequence switch of Figure 3 is also restored to normal.

Upon desiring to signal station 650 the operator actuates key 609 and also 655 the selection of which depends upon the designating number previously given by the calling party.

The actuation of key 609 operates relay 618 and causes the sequence switch of Figure 3 to move to position 2 as before; relays 610, 614 co-operating therewith, and relay 259 being released. When key 655 is actuated the sequence switch, by virtue of sequence switch contact 656 moves into position 14. Contact 611 breaks the circuit of relay 610 six times and thus the arms of switch 627 are advanced to their seventh contacts. When sequence switch contact 657 closes in position 14 relays 612, 616, 606 are energized, and upon their operation a signalling circuit is closed as follows: the negative brush of a current source 658 producing negative pulsating current, arm 629, left

hand front contact and armature of relay 606, conductor 248, wiper 118, conductor 163, sequence switch contact 76, wiper 59, conductor 651, selective signalling apparatus of stations 650 and 660 to ground thereat. The signalling apparatus of station 660 is inactive to the present signalling current, as are also stations 661, 662, and only station 650 is signalled. The operator may use key 655 as many times as she desires, this in no way affecting the setting of switch 627. When the party responds and removes his receiver, she restores keys 655 and 609. Relays 612, 618, 610, 614, 616, 606 release and relays 259, 664 operate. The sequence switch of Figure 3 and switch 627 are restored to normal in the manner already described. Signal 270 and relay 607 operate. These devices release when conversation is completed. The operator then removes plug 268 from jack 239 and thus releases relays 253, 259, 264, 263, 103, and the apparatus fully restores as previously described.

What is claimed is:

1. In a telephone exchange system, the combination with a line having a coin box adapted to operate on either of two polarities of direct current and a selectively signalled party line of a single rotatable selector switch adapted to select a desired polarity of coin box current or a desired selective party line actuating current.

2. In a telephone exchange system, the combination with a plurality of selectively signalled stations, a single pair of conductors for said stations, a source of characterized current for selectively actuating a desired one of said stations, a rotary switch having a plurality of stopping positions, a contact on said switch opened once between each two of said positions and a plurality of keys adapted to render transitional a predetermined number of said positions of a selector controlled by said contact and adapted to selectively actuate said source for signalling said station.

3. In a telephone exchange system, a poly-station line having a plurality of selectively signalled stations, a second line having a coin box, a polarized magnet for said coin box operating in one direction to deposit coins and in the opposite direction to eject coins, a source of signalling current for each of said stations, a source of uni-directional current of one polarity for operating said magnet in one direction, a second source of uni-directional current of opposite polarity for operating said magnet in the opposite direction and a single selecting means for selecting any one of said sources.

4. In a telephone exchange system, the combination with a line having a coin box adapted to operate on either of two polarities of direct current and a selectively signalled party line of a single selector switch

means adapted to select a desired polarity of coin box current or a desired selective party line actuating current.

5. In a telephone exchange system, a poly-station line having a plurality of relatively differently responsive stations, a single station line having a selectively operable electromagnetic device, a plurality of sources of power for signalling said stations and for 10 actuating said device, and a single selector for selecting any one of said sources.

6. In a telephone exchange system, a se-

lective party line, a direct line having a polarized device, a plurality of variously characterized sources of current adapted to 15 signal a party of the line, a plurality of variously characterized sources of current adapted to control the polarized device selectively, and a single selecting means for selecting any one of said sources. 20

In testimony whereof, I hereunto set my hand this 9th day of April, 1921.

GEORGE ALBEN E. LUNDELL.
